UNITED STATES PATENT OFFICE.

CHARLES H. CASWELL, OF NEWPORT, RHODE ISLAND.

BOILER.

SPECIFICATION forming part of Letters Patent No. 367,185, dated July 26, 1887.

Application filed December 31, 1886. Serial No. 223,145. (No model.)

To all whom it may concern:

Be it known that I, CHARLES H. CASWELL, of Newport, in the county of Newport and State of Rhode Island, have invented a new and Improved Boiler, of which the following is a full, clear, and exact description.

The object of my invention is to provide a new and improved boiler in which the steam is quickly generated and the fuel is very economically utilized.

The invention consists in the construction and arrangement of various parts and details, and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a front elevation of my improvement with parts broken out. Fig. 2 is a rear elevation of the same with parts broken out. Fig. 3 is a plan view of the same with parts of the casing broken out. Fig. 4 is a longitudinal sectional elevation of the same on the line *xx* of Fig. 1, and Fig. 5 is a sectional plan view of one side of the same on the line *yy* of Fig. 4 with part of the other side in plan view.

My improved boiler A is preferably placed in the furnace B, constructed as shown, and provided with the front doors, C, the grate-bars D, and the chimney E, below the opening of which is held the perforated shield F, to prevent a too rapid escape of the products of combustion.

The boiler A is provided on its rear end with the upright cylinder F, having the man-hole F' of any approved construction. On top of the cylinder F is placed the steam dome G, provided with the outlets G', connected in the usual manner with the various parts of the machinery to be driven. From the upper part of the cylinder F leads the middle tube, H, toward the front, which connects at its front end with the sidewise-extending branch tubes I and I', having short branch tubes I' connecting with the front chambers, J, J', and J'', which are connected with each other by pipes J''. The chambers J, J', and J'' are supported in any suitable manner at their lower ends in the furnace A.

From the cylinder F branch sidewise the tubes K and K', connected by the short branch pipes K' with the rear chambers, L and L', which are connected at their inner sides by 55 the pipes L' with the cylinder F, and at their bottoms by the bent pipes L'' also with the said cylinder F. The inner sides of the chambers J and J' are connected with the inner sides of the chambers L and L' by means of the horizontal pipes N and N', respectively, and the inner side of the chamber J' is connected by the horizontal pipes O with the upright cylinder F.

It will be seen that the cylinder F, the chambers J, J', J'', L, and L', and the several 65 connecting tubes and pipes are all exposed to the action of the heat generated on the grate-bars D of the furnace A, thus obtaining a large heating-surface, and at the same time establishing a free circulation of water in all the 70 chambers, tubes, pipes, and cylinder F.

The outer covers of the chambers J, J', J'', L, and L' are removable, as shown in Fig. 4, so as to permit of easy access to the pipes N and O for cleaning or for other purposes.

The boiler is charged with water through the inlet-pipes P, opening into the cylinder F near its bottom.

It will also be seen that the boiler as constructed takes up very little room.

Having thus described my invention, what I claim as new, and desire to secure by Letters Patent, is—

1. In a boiler, the combination, with the cylinder F, of the tubes H, I, I', K, and K', 85 and the chambers J, J', J'', L, and L', connected with the said tubes, respectively, substantially as shown and described.

2. In a boiler, the combination, with the cylinder F and the tubes H, I, I', K, and K', 90 of the chambers J, J', J'', L, and L', connected with the said tubes, respectively, and the pipes N and N', connecting the said chambers J and J'' with the chambers L and L', respectively, substantially as shown and described.

3. In a boiler, the combination, with the cylinder F and the tubes H, I, I', K, and K', 95 of the chambers J, J', J'', L, and L', connected with the said tubes, respectively, the pipes N and N', connecting the said chambers J and J'' with the said chambers L and L', and the pipes O, connecting the said chamber J with the cyl-

inder F, substantially as shown and described.

4. In a boiler, the cylinder F, the tubes H, I, and I', and the short branch pipes I², extending downward from the said tubes I and I', in combination with the chambers J, J', and J² and the short connecting pipes J³, substantially as shown and described.

5. In a boiler, the cylinder F, the tubes K and K', and the short branch pipes K², extending downward from the said tubes K and K', in combination with the rear chambers, L and L', and the pipes L² and L³, connecting the said chambers L and L' with the said cylinder F, substantially as shown and described.

6. In a boiler, the cylinder F, provided with 15 the man-hole F', the steam-dome G, held on top of the said cylinder F, the tubes H, I, I', K, and K', and the short branch pipes I² and K², in combination with the chambers J, J', J², L, and L', the connecting-pipes J³, L², and L³, 20 and the horizontally-extending pipes O, N, and N', substantially as shown and described.

CHARLES H. CASWELL.
